UNITED STATES PATENT OFFICE.

MILTON J. FARQUHAR AND HENRY B. FARQUHAR, OF WILMINGTON, OHIO, ASSIGNEES, BY
DIRECT AND MESNE ASSIGNMENTS, TO THE FARQUHAR FURNACE COMPANY, OF WIL-
MINGTON, OHIO, A CORPORATION OF OHIO.

AUTOMATIC FURNACE-REGULATOR.

No. 923,783.

Specification of Letters Patent.

Patented June 1, 1909.

Original application filed March 15, 1902, Serial No. 98,445. Divided and this application filed January 30, 1905.
Serial No. 243,399.

To all whom it may concern:

Be it known that we, MILTON J. FARQUHAR and HENRY B. FARQUHAR, both citizens of the United States, residing at 5
Wilmington, in the county of Clinton and State of Ohio, have invented certain new and useful Improvements in Automatic Furnace-Regulators; and we do hereby declare the following to be a full, clear, and exact description of the invention, such as will enable others skilled in the art to which it 10
pertains to make and use the same.

This invention (for which the present application is filed as a division of our pending application Serial No. 98445, filed March 15, 1902, for an invention entitled "Hot air furnace"), relates to furnaces, inclusive also of stoves or similar heating apparatus, and more particularly to automatic 20
heat-regulating mechanism for rendering the furnace or fire-box self-regulating.

The invention embraces a novel reliable heat-governor operated by the expansion and contraction of the fire-box; the object of 25
which is to effectively control automatically the temperature of the fire-box and regulate the combustion of fuel to best advantage.

In the accompanying drawings, which form a part of this specification, we have 30
represented the automatic heat-regulating mechanism embodying our present invention applied to a furnace such as shown in our aforesaid application Serial No. 98445, wherein the general arrangement of the fire- 35
box, air and smoke flues etc., is horizontal, the products of combustion passing out through an indirect draft flue. While certain claims are made herein to the general combination of such a furnace and automatic 40
governing mechanism, operating on the principles explained, or performing substantially the same functions, it will be understood nevertheless that the present invention is not essentially limited to the construction 45
and embodiment shown, and that the heat-regulator or mechanism constituting the

principal feature of this case is susceptible of other applications and wide utility, while its details of construction and arrangement are also susceptible to modifications. With 50
these remarks in view, the invention will be fully described with reference to the drawings, and then more particularly pointed out and defined in the claims at the end of the description.

Figure 1 of the drawings is a central longitudinal, vertical section of the furnace. Fig. 2 is a fragmentary side elevation showing the relation of the automatic regulating mechanism to the draft and check-doors. Fig. 3 is a perspective view, showing a portion of the air-box broken away and disclosing the interior fire-box. Fig. 4 is a detail view of the adjuster for the regulating mechanism.

Inasmuch as no specific claim is made herein to the improved construction of the fire-box *per se* (since the same is fully described and claimed in our aforesaid application Serial No. 98445), a brief explanation 70
of its construction and operation will be sufficient.

The numeral 1 denotes the outer casing of the air-box; and 2 is the fire-box, 3 its back-plate and 4 its front plate. The fire-box is 75
inclosed within the air-box, except its front plate 4, which is outside the front wall of the air-box and has all the necessary doors or dampers, of which 12 is the fire-door, 13 the ash-door, and 14 the check-door or valve of 80
the smoke-box 10, which is shown located at the base of the furnace front. The fire-box is shown of horizontal tubular form, so that the direction of its expansion and contraction is longitudinal of the furnace.

Within the fire-box, 6 denotes the fire-pit or fuel-space; 5 the ash-pan below the grate; 7 a flue or passage behind the rear bridge-wall 9, or between it and the back-plate 3 of the furnace; and 8 a flue or passage in the bottom 90
of the fire-box from said passage 7 formed along under the ash-pan to the smoke-

box 10. The products of combustion pass over the rear bridge-wall down the passage 7 and forward through the flue or passage 8 to the front smoke-box, which has an outlet opening to the chimney or smoke-pipe 11. Air is of course supplied to the fuel from the ash-door, passing up through the grate; and in this our improved type of furnace, preferably an air-blast is also admitted from the rear of the ash-pan up through a passage in the bridge-wall 9 to the fire-space above the fuel, where it meets the gases at a heat sufficient to ignite the mixture.

The heat-governor or regulating mechanism operates upon the ash-door 13 to control the air admitted to the fuel, and upon the check-door 14 in the smoke-flue or smoke-box 10 to check the draft when necessary. It utilizes a weight, as 15, to open the ash-door, and the force of expansion of the fire-box when heated against an inclosing frame-work not heated to close the ash-door and open the check-door. Said frame-work, as shown, consists of a rear cross-piece 16, having pins or projections 26 that bear against the rear wall 3 of the fire-box to receive the thrust therefrom when the fire-box expands with heat; and a front cross-piece 17; and opposite connecting rods 21 and 22; the rod 21 connecting one end of the rear cross-piece 16 with an adjusting lever 20 attached to the front cross-piece 17, which has a graduated arc 18 and a locking rack 19 for holding said adjusting-lever in place; and the other rod 22 connecting the opposite end of the rear cross-piece 16 with a pendent lever 23 shown fulcrumed at 24 on the front-cross-piece 17; so as to draw said lever inward when the expansion of the fire-box acts against the inclosing frame-work 16, 17, 21, 22, etc., with sufficient force to overcome the weight 15, which tends to hold said lever 23 outward. The lever 23 is rocked on the edge or fulcrum 24 formed on the bar or front cross-piece 17. Pivotedly suspended as at 25 from its lower end is a bent lever 28; the elbow 27 of which is a sliding fulcrum. From the lower part 31 of this lever extends a forward arm 32 carrying the aforesaid weight 15. When the furnace is at low temperature, the weight 15 holds the upper part 30 of bent lever 28 outward, and thereby holds outward the lever 23 also. In this position, a lug 33 on the upper part 30 is out of contact with the lug 29 on the ash-door. Now, when the rising temperature and consequent expansion of the fire-box pulls the connecting-rod 22 rearward, it pulls the lever 23 inward, likewise moving the upper part 30 of the bent lever 28 toward the stove, allowing its fulcrum 27 to slide downward. Said upper part 30 now carries with it the ash-door 13, by virtue of the engagement between the parts 33 and 29. The same movement, if con-

tinued after reaching the position for holding the ash-door closed, changes the fulcrum of the lever 28 to 29, and raises the lower arm 32 and with it the check-door 14, a lug 34 from which overhangs the said arm. These movements tend to close the ash-door and open the check-draft door. The purpose in opening the latter is to supply the necessary draft to the chimney from the outside, instead of from the fire-box; thus relieving draft from the fuel. This mechanism will automatically maintain just the necessary opening of the ash-door to provide the requisite draft for keeping a practically constant temperature. Any increase of temperature will be compensated for by restriction of the ash-door opening, and any sudden or great increase by opening of the check-door. Any decrease from the desired temperature will be compensated for by the outward movement of the lever 23, which draws upward the lever 28, whose lower inclined part 31 engages the lug 29 and opens the ash-door. The inclosing frame-work 16, 17, 21, 22, etc., can be extended or shortened by the adjusting lever 20, so as to cause the expansion of the fire-box to act on the frame at different temperatures; so that the furnace may be arranged to maintain the desired temperature. The said frame-work may surround the fire-box as herein described, or may occupy one side only, being suitably connected with the front and rear plates of the fire-box.

The broad principle of the heat-regulator is the transmission of motion due to expansion of the fire-box through a non-expanding member to a suitable lever-mechanism for controlling the position of the draft or check-doors. To secure sufficient action, it is important that the non-expanding member be kept as cool as possible; and it is therefore protected by a shield, being in the present instance placed outside the casing of the air-box where it is shielded from the rays of heat from the fire-box and where it is kept cool by exposure to the surrounding air.

We claim as our invention and desire to secure by Letters Patent of the United States:—

1. In a furnace, the combination with an expandible fire-box and surrounding air-box or casing for the medium to be heated, of a four sided frame-work not affected by heat inclosing the air-box and arranged to receive the thrust from expansion of the fire-box, and regulating mechanism for the draft opening or openings operated by said frame-work when moved by expansion of the furnace.

2. In a furnace, the combination with a heater having a draft-door, of a thermostatic governing mechanism comprising a pendent lever, a second intermediately-fulcrumed lever pendent from said first men-

- tioned lever and connected to said door, a weight carried by said second lever and tending to hold the same in position to maintain said door open, and heat-governed 5 means connected with said first mentioned lever for moving the same under rise of temperature in a direction which moves the second lever in a manner to close said door.
3. In a furnace, the combination with an 10 expansible fire-box provided with a draft-door and check-door, of a vertically-disposed lever (28) intermediately fulcrumed and connected with said draft-door and provided with a weight for holding said 15 lever in a position to maintain said draft-door open, and mechanism connected with said fire-box and actuated by expansion thereof and connected with said lever for moving the same in a direction to close said 20 door, and means whereby said check-door is controlled by said lever.
4. The combination of a horizontally-disposed expansible fire-box, and a surrounding casing for medium to be heated, 25 of a non-expanding frame-work surrounding said casing and comprising front and rear cross-pieces at the front and rear of the furnace respectively, a tie-rod connecting said cross-pieces at one side of the furnace, a damper-controlling lever fulcrumed on one of said cross-pieces, and a tie-rod connecting the opposite cross-piece and said lever and arranged at the other side of the furnace, and means extending from one end 30 of the fire-box through said casing and bearing against one of said cross-pieces, whereby said frame-work receives the thrust of expansion of the fire-box.
5. The combination with the expansible 40 fire-box, of the non-expanding frame-work comprising front and rear cross-pieces, a damper-operating lever fulcrumed on one cross-piece, a rod connecting said lever with the opposite cross-piece, an adjusting lever 45 connected to one cross-piece and having means for locking it in place, and another rod connecting said lever and the other cross-piece.
6. The combination with the ash-door and 50 check-door, of a pendent lever, a bent lever pivotally-suspended therefrom whose elbow constitutes a sliding fulcrum, and having a lower arm underlying a lug on the check-door, temperature-controlled means for 55 moving said pendent lever inward and outward, inward movement thereof causing inward movement of the upper part of said bent lever, and means whereby on such inward movement of said upper part it engages and moves inward the ash-door, while 60 the continued movement after the door is closed causes the said lower arm to lift the check-door.
7. A furnace having, in combination, a 65 horizontally disposed tubular fire-box provided with a front fire door and ash door thereunder, said fire-box having an internal grate and ash pan so arranged as to provide in the rear and bottom of the fire-box an indirect draft and smoke passage, said 70 passage having its final outlet at the base of the front of said fire-box, a smoke-pipe or chimney in communication with said final outlet, a check-door under the ash-door for controlling admission of air into said 75 smoke-pipe, and mechanism mounted on the furnace operated by expansion and contraction of the fire-box and including a front pendent lever connected with the ash-door and check-door for automatically controlling the same.
8. In a furnace, the combination with an 80 expansible fire-box and surrounding air-box or casing for the medium to be heated, of a frame-work not affected by heat inclosing 85 the casing, means for imparting the thrust of expansion of the fire-box to said frame-work, a draft damper, and a lever operated by said frame-work for controlling said damper.
9. In a furnace, the combination with a 90 horizontally expansible fire-box and surrounding air-box or casing for the medium to be heated, of a non-expanding frame-work surrounding the casing, thrust pins interposed between the rear cross-piece thereof 95 and the back of the fire-box, and a damper-controlling mechanism actuated by said frame.
10. The combination with the expansible 100 fire-box, of the non-expanding frame-work surrounding the furnace and comprising front and rear cross-pieces, a damper-operating lever fulcrumed on one cross-piece, a tie-rod connecting said lever and the opposite cross-piece at one side of the furnace, 105 and an adjustable tie-rod connecting said cross-pieces at the opposite side of the furnace, the said frame-work being adapted to receive the thrust of expansion of the fire-box.
11. In a furnace, the combination with the hinged ash-door having a lug thereon, of a pendent bent lever whose elbow constitutes a sliding fulcrum, the upper part of said lever having a lug overlying the lug on the 110 ash-door, heat-controlled means connected with said lever for drawing its upper part inward as the temperature rises, and a weight acting upon the lower part of said lever.
12. In a furnace, the combination with the hinged ash-door having a lug thereon, of a pendent bent lever whose elbow constitutes a sliding fulcrum, the upper part of said lever having a lug overlying the lug on the ash-door, heat-controlled means connected with 115 said lever for drawing its upper part inward as the temperature rises, a hinged check-door.

having a lug overlying the lower part of said lever, and a weight acting upon the lower part of said lever.

13. The combination with a longitudinally expansive heater, provided with a draft door, of a pendent lever, a second lever, provided with a weighted end, pendent therefrom and adapted to engage said draft-door and normally hold it open, and means connecting said first mentioned lever and said

heater to rock both of said levers and close said door when the heater expands.

In testimony whereof we affix our signatures, in presence of two witnesses.

MILTON J. FARQUHAR.
